CLAIM

The ornamental design for a display screen with graphical user interface, as shown and described.

DESCRIPTION

FIG. 1 is a front view of a display screen with graphical user interface showing our new design;

FIG. 2 is a front view of a display screen with graphical user interface showing a second embodiment of our new design; FIG. 3 is a front view of a display screen with graphical user interface showing a third embodiment of our new design; and,

FIG. 4 is a front view of a display screen with graphical user interface showing a fourth embodiment of our new design. The broken lines shown in the drawings represent portions of the embodiments of the graphical user interface for a display screen that form no part of the claimed design.

1 Claim, 4 Drawing Sheets(56)
